ABSTRACT: Water closet supply tanks of the type embodying a float regulating the water supply, according as the level of water rises in said tank. Particularly, a control tank positioned within said water tank, so as to encompass the float and ensure cutting off of the water supply if the discharge valve remains open in the water tank.

CONTROL FOR A WATER CLOSET

BACKGROUND OF THE INVENTION

1. Field of the Invention

A great deal of attention has been directed to providing an inexpensive method of preventing continued running or wasting of water when a failure or breakage occurs in the water closet, such as the tank itself, the flush valve, flush-valve seats, stand pipe or overflow pipe, control handle and flush-valve controls including the chain and linkage. It is estimated that a single water closet continuously filling and emptying wastes water equivalent to total water closet usage in 25 homes. Estimated total waste from one water closet is 4,320 gallons within a 24-hour period.

2. Description of The Prior Art

Earlier inventors have attempted to solve the problem by developing float controls which are attached to the discharge valve in the water tank. Braswell U.S. Pat. No. 2,740,129 and Petrie U.S. Pat. No. 2,908,018 are typical in this respect. Such devices utilize a complicated mechanical linkage to attempt closing of the discharge valve upon malfunction, but do not necessarily ensure that the water supply being fed to the tank will be cut off. The present invention, on the other hand, is directed to closing of the water supply valve, independently of the operation of the discharge valve. As a result, the water filling valve is closed immediately as the control tank senses a malfunction due to the discharge valve remaining open.

SUMMARY OF THE INVENTION

According to the present invention, a control tank is placed within the water tank, so that it has an open-ended top encompassing the conventional water tank control float. The control tank has a discharge drain at its bottom and a ball-cock seat encompassing the discharge drain. The control tank discharge drain is positioned above the level of the water tank discharge valve and a buoyant ball-cock valve is seated within a ball-cock seat above the drain. As water enters the tank and the tank fills, water enters simultaneously through the discharge drain of the control tank, filling the control tank, lifting the buoyant ball cock and the control float. As the control float rises to the desired level, the water-supply valve is cut off. If the water tank discharge drain remains open and water is continued to be fed into the tank, the ball-cock valve will fall onto its seat, closing the control tank. The closed control tank will then be filled via a control-supply conduit, enabling a rising of the water and the control float, so as to effect a precise cutoff of the water supply independently of the malfunction of the discharge drain.

BRIEF DESCRIPTION OF THE DRAWINGS

FIG. 1 is a partially sectional side elevation of the control tank fitted into a conventional water closet so as to encompass water-control float and control linkage, the water-control float being raised to water cutoff position;

FIG. 2 is a similar view, showing a modified float and ball cock, raised to water cutoff position as the tank fills with water;

FIG. 3 is a partially fragmentary side elevation of the construction shown in FIG. 1 wherein the control float is raised to water cutoff position in the control tank as the tank discharge remains open and in a state of malfunction; and

FIG. 4 shows the FIG. 2 modification in emergency water-valve-closed position, as the tank-discharge valve remains open and in a state of malfunction.

DESCRIPTION OF THE PREFERRED EMBODIMENTS

FIG. 2 is a drawing of a water closet tank and operative parts with a water-valve control tank depicted as tank 11, float chamber and valve seat 12, control float and stem 13, control valve 14, refill Y-fitting 4 and extension tube 3. FIG. 2 depicts the ball cock in the closed or off position and the water closet tank 1 in the filled stage. It should be noted that in this

drawing the control float 13 has floated upward because of its being surrounded by water and has lifted the control valve 14 into a raised or open position allowing water to flow freely between the control tank 11 and the water closet tank 1 and, therefore, causing the ball-cock float 10 to be in the upward position or off position for the ball cock. During a normal flushing operation, the control tank does not interfere with the normal operation of the ball cock and of the ball cock float 10.

In a normal flushing operation, the handle 7 moves the ball valve 15 to an upward position. As the water recedes from the water closet tank 1, it also recedes from the control tank 11 passing through the float chamber and valve seat 12 and finally through the ball-valve-opening seat 16. This receding water level in the control tank 11 will allow the ball-cock float 10 to fall to the lower level and activate or cause to engage the cock whereupon the ball water inlet refill tube 17 will begin flooding the water closet tank 1 with water and at the same time will be supplying water through the refill tube into the stand pipe or overflow pipe 5 and, at the same time, supplying water through the Y-fitting 4 and extension tube 3 which will refill control tank 11.

When flush valve 15 is closed or seated, the water level will rise from the bottom of the water closet tank 1 and will cause the float and stem 13 to lift the control valve 14, creating an equal water level between the water closet tank 1 and the water-valve control tank 11, resulting finally in the raising of the ball-cock float 10 to a level which will cut off or close the ball cock.

30 FIG. 4 illustrates a situation where the flush valve 15 did not return to its closed position, as in the case of a hanging handle 7. In this event, the ball cock would be open and discharging water through the refill tube 17 and through the extension tube and Y-fitting 3 and 4. Because the water level in the 35 water closet tank 1 cannot rise due to the leakage (in this case, a hanging flush-valve handle 7), the float and stem 13 and valve 14 will not be floating but will be in the lower position as illustrated in FIG. 4. At the same time, the refill tube 4 is refilling the control tank 11, which causes the ball cock float 40 10 to rise to its upper level, as shown in FIG. 2 and, of course, cuts off ball cock from allowing any additional water to be wasted.

In the water closet failure, as illustrated above, the ball cock will run approximately 1 minute or approximately 3 gallons of 45 water before the control tank will fill enough to cut off the ball cock (without a control tank, the ball cock would waste 4,320 gallons per 24 hours). At this point, the water closet will no longer provide a flushing action, as is apparent in FIG. 4. To 50 reset the water-valve-control tank so that a normal flushing action can again be accomplished, it would be necessary to repair whatever is not allowing the water closet tank 1 to refill (in the above-mentioned example, an adjustment to the hanging flush-valve handle 7).

To reset control tank 11 and water closet tank 1 for normal 55 operation, you would simply depress the ball-cock float 10 by hand until the water level within the water closet tank 1 and the water level within the control tank 11 are up to normal off level as shown in FIG. 1.

60 The built-on tank, as illustrated in FIGS. 1 and 3, operates in exactly the same manner and uses the same parts and components as the add-on tank, FIGS. 1 and 2, modified float 10' being supported reciprocably upon ball-cock extension 19.

65 I claim:

1. In a water closet of the type embodying a water tank with a water supply conduit having a ball-cock-filling valve, a ball-cock float positioned in said tank and connected to said ball-cock-filling valve and a manually operable discharge drain ball valve, a control tank assembly positioned within said water tank comprising:

a. a water-control tank in communication with said water-supply conduit, encompassing a control float and defining an open top, and a discharge drain communicating with said water tank near the bottom of said control tank;

- b. a float chamber supported above said discharge drain and defining a control-valve seat at its top;
  - c. a buoyant ball-control float and attached control valve, said float supported within said chamber and said valve supported above said seat, so as to float above and open said seat as the water level rises in said water tank and said control tank and so as to rest upon and close said drain, as the water level falls within said water tank and said control tank.
2. In a water closet, a control tank as in claim 1, said float chamber having a reduced-diameter top aperture defining said seat and coaxially aligned with said float chamber and said control float and control valve consisting of a control valve positioned above said seat and float member positioned beneath said seat, whereby filling of water in said chamber through said discharge drain raises the control valve above said seat and discharge of water through said control drain causes said valve to fall upon said seat and to hold water in said control tank.
3. In a water closet a control tank as in claim 2, the bottom

20

of said control tank being positioned above the level of said discharge drain in said water tank, so that water filling into said water tank enters said control tank through the discharge-drain float chamber, and valve seat.

5. 4. In a water closet, a control tank as in claim 3, said control tank being positioned upon said water supply conduit such that said float reciprocates upon a vertical extension of said water conduit while being linked to said water-supply-filling valve.
5. In a water closet, a control tank as in claim 3, including an extension tube extending independently from said filling valve to the top of said control tank.
6. In a water closet, a control tank as in claim 5, said control float and control valve further including:
- 15 1. a top spherical control valve;
2. a bottom float of greater dimension than said valve seat; and
3. a relatively thin stem interconnecting said control valve and said control float.
